(57) CLAIM

The ornamental design for an ash insert, as shown and described.

DESCRIPTION

FIG. 1 is a perspective view of an ash insert, showing my new design;

FIG. 2 is a top plan view thereof;

FIG. 3 is a bottom plan view thereof;

FIG. 4 is a front plan view thereof;

FIG. 5 is a rear plan view thereof;

FIG. 6 is a left side plan view thereof;

FIG. 7 is a right side plan view thereof; and,

FIG. 8 is an elevational view of an ash insert, illustrating a tray for inserting into the ash insert and a ceramic grill charcoal receptacle into which the ash insert is inserted thereto.

The broken lines showing a tray and charcoal receptacle in the views depict unclaimed subject matter only and form no part of the claimed design.
